CLAIM

The ornamental design for a helmet with face shield, as shown and described.

DESCRIPTION

FIG. 1 is a front and top perspective view of a helmet with face shield showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is another front and top perspective view thereof, showing the face shield in a raised position;

FIG. 9 is a rear and bottom perspective view of the helmet with face shield of FIG. 1; and,

FIG. 10 is an enlarged view of the portion 10 encircled in FIG. 1.

The evenly dashed broken lines in the figures illustrate portions of the helmet with face shield that form no part of the claimed design.

The dot-dot-dash broken lines in the drawings encircle portions of the claimed design that are illustrated in enlargements and form no part of the claimed design.
